CONTROL FOR PAPERMAKING MACHINES

Emmons F. Lewellen and Darcy E. Lewellen,
Columbus, Ind.

Application May 19, 1948, Serial No. 27,938

10 Claims. (Cl. 92—46)

1

The present invention deals with paper making machines, and is concerned primarily with the controls employed for the purpose of accurately governing the thickness of paper which is produced by a machine.

In order to clearly set forth the objects and advantages of the present invention, it is necessary to refer to certain essential elements of a paper making machine of the type with which this invention is concerned.

Such a machine ordinarily includes a head box which receives the stock in liquid form and in which the stock is maintained at a predetermined level. The head box is provided with an outlet, the effective area of which is controlled by an adjustable gate. From this outlet a conduit extends downwardly to a manifold. From the latter a plurality of individual conduits extend downwardly to a corresponding number of cylinder vats.

At this point it is well to note that the flow of the stock from the head box down through the manifold to the cylinder vats is under gravity action and therefore takes place at a substantially constant velocity.

In each cylinder vat there is a wire screen cylinder together with means for creating a vacuum condition on the interior thereof. The stock is thus drawn to each cylinder and the water exhausted from the center leaving the fibrous pulp on the screen.

The cylinders are power driven and as they rotate the layer of fibers from each cylinder is picked up by a felt in the form of an endless belt on which the several layers are superimposed to make up the paper thickness. From this felt the sheet of paper is transferred to a second felt on which it is subjected to the action of pressing rolls which eliminate a large amount of the water so that when the paper sheet leaves this second felt it has a self-sustaining body. It is then passed on through drying and calendering rolls from which it is either cut into sheets or wound into rolls.

It is evident that the thickness of the sheet of paper which is produced by the machine may be determined by the thickness of the sheet as it leaves the second felt in which it has achieved a self-sustaining body formation and before being subjected to the action of the drying and calendering rolls.

For many years it had been the practice in this art to determine the thickness of paper which was being produced by a machine by the so-called "cut and try" methods. This means that

2

the machine was operated to produce a sheet of paper. If this sheet was found to be too thick the gate controlling the outlet in the head box was adjusted to reduce the effective area of the outlet and thereby decrease the amount of stock which was delivered to the cylinder vats. If the sheet was too thin the effective area of the outlet was enlarged to increase the supply of stock, and these operations were repeated until the paper of a desired thickness was being produced by the machine. Obviously, such methods involved considerable waste and those engaged in paper making production have long since discarded such cut and try methods.

Some years ago it was proposed to obtain a better control of the thickness by locating caliper rolls at the point where the paper first achieves its self-sustaining body and these caliper rolls were tied up with gate adjusting mechanism so that if the paper sheet reaching these rolls were too thick the gate would automatically close, or, if it were too thin the gate would automatically open. However, with such an arrangement it was impossible to obtain an accurate control of the paper thickness because of the time period which elapses from the moment the stock passes the gate until it reaches the caliper rolls. Thus, if the paper were too thick and the caliper rolls affected the gate adjusting mechanism so as to move the gate in a direction restricting the size of the opening, this action of the caliper rolls would not cease until the paper reaching them had been reduced in thickness to that for which the machine had been adjusted. Therefore, the closing movement of the gate will not have been terminated soon enough and the gate will close too far to cause the paper to be thinned out beyond the degree desired.

The problems and conditions attending this time factor have been recognized by those skilled in this art and in the patent to Lewellen et al., 1,768,088 there is disclosed certain control devices which accommodate this time factor. In this patent a control device is provided which imparts a certain amount of movement to the gate for each cycle of operation. The time period of each cycle is theoretically supposed to correspond to the time which it takes the stock to travel from the outlet of the head box to the caliper rolls. However, in the device of the patent the mechanism which determines the length of a cycle is driven from an idler roll which is in turn driven at a speed commensurate with the speed of travel of the paper in the machine. While a device such

as shown in the patent may be adjusted to give accurate and completely satisfactory performance for one speed of operation of the machine, it is not susceptible of adjustment to other speeds and still afford the same satisfactory operation. This is due to the following reasons:

Paper making machines of the type with which this invention is concerned which are actually used by those engaged in the manufacture of paper, are intended to operate at speeds over a fairly wide range. For exemplary purposes, it may be assumed that a machine of this type is designed to afford satisfactory operation over a range of 10 to 80 feet a minute. The velocity at which the sheet moves from the first cylinder in the cylinder vats to the caliper rolls is the speed of the machine and is subject to this variation. However, it will be recalled that the velocity of the stock in its travel from the head box outlet to the cylinder vats is substantially constant. Thus, the time required for the stock to travel from the head box outlet to the caliper rolls comprises a constant plus a variable. The constant is the time it takes the stock to reach the first cylinder vat, and the variable is the speed of the machine. The constant may be represented by the letter x and the variable by the letter y .

If the control device is adjusted so as to give proper controlling action for a given speed, the cycle would be equal to x plus y . Let us assume that the speed of the machine is doubled. Under this condition the proper period for the cycle should be $x + \frac{1}{2}y$ and not $\frac{1}{2}(x+y)$.

In the device of the patent above referred to the latter condition obtains and in accordance with the present trend of using high speed machines including a comparatively large number of cylinders, cylinder vats, drying and calendering rolls, it has not proved to be satisfactory.

With the foregoing conditions in mind, the present invention has in view as its foremost objective the provision of a paper making machine of the type indicated which includes control mechanism for accurately controlling the thickness of the paper being produced and which mechanism is characterized as being capable of accurately conforming to the time interval required for the stock to travel from the outlet in the head box to the caliper rolls.

A further object of the invention is the provision in a paper making machine of the type indicated of control mechanism which is either manually adjustable or automatically operable to control the thickness of the paper being produced over a wide range of speeds for the paper making machine.

In carrying out these ideas in a practical embodiment the control mechanism includes certain instrumentalities which determine the length of the cycle which provides for the intermittent operation of the gate and these instrumentalities are not directly commensurate with the speed of operation of the machine, but are driven by an independent power source such as an electric motor. A somewhat more detailed object of the invention is the provision of means for the manual adjustment of this power source to vary the cycle.

A further object is the provision of means for automatically varying the length of the cycle in accordance with variations in the speed of the machine but in which the cycle accurately conforms to the time required for the stock to

travel from the head box outlet to the caliper rolls.

Various other more detailed objects and advantages of the invention such as arise in connection with carrying out the above noted ideas in a practical embodiment will, in part, become apparent and, in part, be hereinafter stated as the description of the invention proceeds.

The invention therefore comprises control mechanism for paper making machines of the type above indicated and which is characterized as being capable of adjustment over a wide range of speed of operation for a machine and at the same time intermittently adjusting the gate over a cycle the length of which accurately conforms to the time it takes the stock to travel from the head box outlet to the caliper rolls.

For a full and more complete understanding of the invention reference may be had to the following description and accompanying drawings in which:

Figure 1 is a perspective view of the head box and manifold which may be taken as the beginning of the paper making operation for the purposes of this specification;

Figure 2 is a side view in elevation, but somewhat diagrammatic, bringing out the manifold, cylinder vats, and associated parts which bring the paper sheet into a self-sustaining body condition;

Figure 3 is a side view similar to Figure 2 showing the remainder of the machine including the drying rolls, calendering rolls, and cutting mechanism;

Figure 4 is an enlarged detailed showing, partly in section and partly in elevation, of the gate controlling unit;

Figure 5 is an enlarged detailed sectional view taken about on the plane represented by the line 5-5 on Figure 4;

Figure 6 is an enlarged detailed perspective of the caliper rolls and control mechanism immediately associated therewith;

Figure 7 is another detailed showing in elevation with parts broken away and shown in section of the contacts of the control mechanism of Figure 6;

Figure 8 is a detailed sectional view through the contacts taken about on a plane represented by the line 8-8 on Figure 7;

Figure 9 is an enlarged detailed perspective of the cycle determining mechanism that is manually adjustable;

Figure 10 is another detailed perspective showing a modified form of cycle determining mechanism which is automatic; and

Figure 11 is a wiring diagram bringing out the manner in which the various control mechanisms are electrically interconnected and tied up with the operation of the machine.

General assembly

The general assembly of the machine is depicted in Figures 1, 2 and 3. A head box is shown in Figure 1 and is represented in its entirety by the reference character B.

The box B may be of any suitable formation such as the rectangular shape illustrated, and has a side wall 10 formed with an outlet opening 11, the effective area of which is controlled by a gate 12. Another wall of the box B such as that shown at 13 is formed with an overflow port at 14, with which communicates an overflow pipe 15.

Stock in the usual liquid formation comprising water and fibers is introduced into the box B through the inlet pipe shown at 16. This stock is maintained at the level represented by the broken line 17 as this level is determined by the position of the overflow opening 14.

A manifold is represented at 18 and a conduit 19 extends downwardly from the outlet 11 to the top of the manifold. Mounted within the manifold is a screen 20 through which the stock must pass. The bottom wall of the manifold 18, which is designated 21, is formed with a plurality of outlet openings with which communicate conduits 22, 23, 24, 25 and 26.

Upon referring now more particularly to Figure 2 it will be noted that there is an assembly of cylinder vats comprising the vats 27, 28, 29, 30 and 31. The top wall of each vat is formed with an opening with which communicates one of the conduits 22 to 26, inclusive. Thus, the conduit 22 communicates with the opening in the top wall of the vat 27; the conduit 23 with the opening in the top of the vat 28; the conduit 24 with the opening in the top of the vat 29; the conduit 25 with the opening in the top of the vat 30; and the conduit 26 with the opening in the top of the vat 31.

It is evident that stock flows from the outlet 11 in the head box B down through the manifold and conduits above described to the vats 27 to 31, inclusive, under gravity action. Rotatably mounted within the vat 27 is a cylinder 32 that is of a construction well known and conventional in this art. The cylinder 32 comprises appropriate supporting structure in the form of spiders and on which is mounted a cylindrical screen. At each end there is a head and one of these heads is formed with an exhaust opening 33. A roll shown at 34 cooperates with the cylinder 32 in that a felt 35 is passed between the roll 34 and the cylinder 32.

As the stock is introduced into the vat 27 it passes around the outside of the cylinder 32. A suction is created at the exhaust port 33 and this draws the water into the interior of the cylinder leaving the fibers on the screen. As the cylinder is rotated the layer of fibers so formed is picked up on the underface of the felt 35.

The vat 28 has rotatably mounted therein a cylinder 36 formed with an exhaust port 37 and with which cooperates a roll 38. These elements are the exact counterpart of the elements 32, 33 and 34 in the vat 27 and operate in the same manner.

Likewise, the vat 29 has rotatably mounted therein a cylinder 39 having an exhaust port 40 and with which cooperates a roll 41. These members function in the manner described.

Similarly, the vat 30 is provided with a cylinder 42 having an exhaust port 43 and with which cooperates a roll 44.

Finally, the vat 31 is provided with a cylinder 45 having an exhaust port 46 and with which cooperates a roll 47.

The end wall of the vat 27 is formed with an opening 48 and mounted in this opening 48 is a roll 49. The felt 35 passes between the roll 34 and cylinder 32 and thence over the roll 49. The top wall of the vat 31 is formed with an opening 50 and the felt 35 passes through this opening and then between the roll 47 and cylinder 45. It will be noted that the partitions separating the several vats are formed with horizontal slots through which the felt 35 passes.

The felt 35 takes the form of an endless belt.

After passing over the roll 49 it passes beneath a pressure roll 51 and from there upwardly over a roll 52. From the roll 52 the belt continues back over another roll 53 after which it passes down through the opening 50.

After the lower ply of the felt 35, that is the ply which passes through the several cylinder vats, passes over each cylinder 32, 36, 39, 42 and 45, it is urged thereagainst by the rolls 34, 38, 41, 44 and 47, and this underface of the felt picks up the layer of fibers which has formed on the cylindrical screen surface of each cylinder. These layers are superimposed one upon the other to form the thickness of the paper sheet being produced.

A second felt is represented at 54 and also takes the form of an endless belt that passes over pressure rolls 55, 56 and 57 and over the guide rolls 58 and 59. It will be noted that this felt 54 at 10 the roll 51 passes beneath the felt 35. Thus, the sheet of paper which has been built up on the underface of the felt 35 is transferred to the upper face of the felt 54. Cooperating with the pressure roll 56 is a complementary pressure roll 20 50. As the paper sheet on the felt 54 passes between the rolls 56 and 60 a substantial amount 25 of the water is squeezed therefrom and this action is repeated as the paper sheet passes between the pressure roll 55 and a complementary pressure roll 61.

As the paper sheet leaves the bight of the rolls 30 55 and 61 it will have achieved a self-sustaining body. This paper sheet is represented at P and is shown as passing over guide rolls 62 and 63 and 35 thence between a pair of caliper rolls 64 and 65 which form a part of a control unit represented at C, to be described later in detail.

After passing between the caliper rolls 64 and 40 65 the paper P is passed over a series of drying rolls shown at 66, 67, 68, 69, 70, 71, 72, 73 and 74. It is to be understood that the invention is not to be limited to the particular number of drying rolls illustrated, because this number may be varied in accordance with principles well known 45 in this art.

After leaving the drying roll 74 the paper P is passed between a series of calender rolls. These are shown at 75, 76, 77, 78, 79, 80, 81, 82, 83, 84, 50 85 and 86. From the last calender roll 86 the paper P passes over a guide roll 87 and thence to a cutting machine represented diagrammatically at 88. This cutting machine cuts the paper into sheets which are stacked as indicated at 89. It is evident that the cutting machine 88 and stack 55 89 could be replaced by a rolling device which would simply roll the paper P after it leaves the guide roll 87 into a rolled formation.

It is evident that after the paper sheet P leaves the rolls 55 and 61 it has a self-sustaining body and will have achieved its thickness. Thus, when 60 this sheet passes between the caliper rolls 64 and 65 any variations in the thickness thereof will be effective through the several control units now to be described to adjust the gate 12 so as to vary the effective area of the outlet 11. These control devices will now be described.

Gate operating mechanism

As shown in Figure 1, a unit U is mounted on 70 the top of the box B and extending downwardly from this unit U is a link 90 that is connected to the gate 12. The mechanism of the unit U is effective through this link 90 to raise or lower the gate 12.

Referring now more particularly to Figure 4, it

will be noted that the unit U comprises a casing defined by side walls 91 and 92, a top wall 93, and a bottom wall 94. The top wall 93 includes an arched part 95 which accommodates the extension of the side wall 92. Extending downwardly from the joinder of the arm 95 and top 93 is a vertical partition 96 that is integrally connected at the bottom with a horizontal partition 97. Another horizontal partition 98 extends between the vertical partition 96 and the side wall 92, and another comparable horizontal partition is shown at 99.

Mounted on the partition 97 is an electric motor 100 having a drive shaft 101 on which is drivably mounted a worm 102. Meshing with the worm 102 is a worm gear 103 that is drivably mounted on a shaft 104. The shaft 104 is journaled in the partition 96 and at the end remote from the worm 103 drivably carries a bevel gear 105. A vertical shaft 106 is journaled in the horizontal partitions 98 and 99 and drivably mounted thereon is a bevel gear 107 which meshes with the bevel gear 105. Drivably mounted on the lower end of the shaft 106 is a gear 108 that meshes with a pinion 109 that is drivably mounted on a screw stem 110. The screw stem 110 is arranged vertically and has its opposite ends journaled in the partition 97 and bottom wall 94, respectively. Threaded on to the screw stem 110 is a nut 111 from which projects an arm 112. It will be noted that the link 90 is pivotally connected at its upper end to the arm 112 with the pivotal connection being shown at 113. This link 90 passes through an opening 114 formed in the bottom wall 94.

Extending outwardly from the nut 111 in a direction substantially opposite to the arm 112 is a second arm 115. This arm may be formed with an opening through which passes a vertical guide rod 116 having its upper and lower ends anchored in the partition 97 and bottom wall 94, respectively. A slide rod 117 has its lower end slidably received in an opening 118 formed in the bottom wall 94 and adjacent to its lower end carries a collar 119. An expansion coil spring 120 bears against the collar 119 at the top and the wall 94 at the bottom. The upper end of the slide rod 117 is reduced in diameter as shown at 121 and is slidably received in an opening 122 formed in the partition 97. This opening 122 is counterbored as indicated at 123 and an expansion coil spring 124 is disposed around the reduced end 121 within the counterbore 123.

It is evident that the springs 120 and 124 normally maintain the slide rod 117 in a neutral position but permit a certain amount of sliding action on the part of the rod. A collar 125 is mounted on the slide rod 117 on the upper side of the arm 115 whereby the lower face of the collar 125 is adapted to be engaged by the arm 115. A second collar 126 is mounted beneath the arm 115 whereby its upper face is adapted to be engaged by the arm 115.

It is evident that as the arm 115 is moved upwardly it will engage the collar 125 to shift the slide rod 117 upwardly, or, as it reaches the lower limit of movement it will engage the collar 126 to shift the slide rod 117 downwardly.

A switch is referred to in its entirety by the reference character S, and is shown as mounted on the inner face of the wall 91. The switch S comprises a central contact 127 that is carried at the end of an arm 128, an upper contact 129 carried by a spring arm 130, and a lower contact 131 carried by a lower spring arm 132. A

tension spring 133 has its opposite ends connected to the arms 130 and 132 and normally urges the contacts 129 and 131 into engagement with the contact 127. Extending outwardly from the slide rod 117 is an arm 134, the free end of which is disposed between the free ends of the arms 130 and 132.

The switch S is intended to function as a limit switch for the motor 100. When both the contacts 129 and 131 engage the intermediate contact 127, as illustrated in Figure 4, the circuit to the motor 100 is closed so far as the switch S is concerned. Thus, if the nut 111 should be moved upwardly sufficiently far, arm 115 engages the collar 125 to shift the slide rod 117. This causes a corresponding movement on the part of the arm 134 which will engage the free end of the spring arm 130 and lift the contact 129 from the contact 127 thereby interrupting the circuit to the motor. In the same way, if the nut 111 is moved downwardly a sufficient distance the arm 115 engages the collar 126 and shifts the slide rod 117 downwardly, thereby causing the arm 134 to engage the free end of the spring arm 132 and separate the contact 131 from the contact 127 to interrupt the circuit. With this arrangement it is evident that the gate 12 can be neither opened nor closed beyond a certain predetermined extent.

Drivably mounted on the upper end of the shaft 106 is a bevel gear 135 and meshing with this bevel gear 135 is a complementary gear 136 that is drivably mounted on a shaft 137, the opposite ends of which are journaled in the partition 96 and the side wall 92. A disc 138 is drivably mounted on the shaft 137 and the outer face thereof is formed with a raised contact surface 139. Mounted in the side wall 92 is an insulating member 140 in which are imbedded a pair of contacts 141 and 142 (see Figure 5), which are connected to the terminals shown at 143. It is evident that these contacts 141 and 142 are adapted to be bridged and conductively connected by the upraised contact faces 139.

The terminals 143 are connected by cable as shown at 144 to a signal light 2 (Figure 11). Thus, as the motor 100 is operated it will, through the driving connections above described, rotate the disc 138 and upon every full rotation of the disc 138 the control surfaces 139 will close the circuit to the signal light 2 and thus indicate that the gate 12 (Figure 1) is being moved.

Caliper control unit

Upon referring to Figures 6, 7 and 8 the control unit C which is associated with the caliper rolls 64 and 65 will now be described.

Upstanding from the supporting framework of the machine is a stanchion 146 which carries at its upper free end a bracket 147 on which is mounted a panel 148. The panel 148 carries certain mechanism about to be described and which mechanism is adapted to be enclosed by a casing 149 which is hingedly mounted on the panel as represented at 150.

The caliper roll 65 is mounted in fixed position by a clamp 151 that is anchored to the stanchion 146 and from which extends an arm 152 on which the caliper roll 65 is rotatably mounted. The upper caliper roll 64 is rotatably mounted between the arms of a yoke 153, the latter being integrally connected to one leg 154 of a U-shaped plate that is pivotally mounted as represented at 155 on the panel 148. This

U-shaped plate has a second leg 156. Upstanding from the upper edge of the leg 156 adjacent to its free end is a pointed pin 157 which bears against the lower edge of a lever 158 that is pivotally mounted as shown at 159 on a slide block 9.

The block 9 has a tongue (not illustrated) that is received in a slot 8 and the two cooperate to act as a guide for the block 9 in its sliding movements. A shaft 7 has a lower threaded end that is screwed into a threaded bore in the block 9. The upper end of the shaft 7 drivably carries an operating member 6 which may be availed of to rotate the shaft 7 and adjust the position of the block 9 and pivot 159 carried thereby. A calibrated cylinder 5 and pointer 4 cooperate to indicate the adjusted position of the pivot 159.

The free end of the lever 158 also carries a pin 160 that engages the lower edge of a lever 161 that is pivotally mounted as shown at 162 on the panel 148. A gear sector 163 is pivotally mounted as shown at 164 on the plate 148 and has a lower face 165 that is engaged by the point of a pin 166 that is carried at the free end of the lever 161.

It is evident that the several levers comprising the U-shaped plate made up of legs 154 and 156 and levers 158, 161 and gear sector 163, function as a means for amplifying any movement on the part of the caliper roll 64, which might be caused by variation of thickness in the paper sheet P so as to provide a substantial amount of movement at the gear teeth 167 on the gear sector 163. A pinion 168 is pivotally mounted on the panel 148 and engages the gear teeth 167 so as to be operated thereby. A contact arm 169 is drivingly connected to the pinion and the free end of this arm is adapted to engage any of the contacts 170, 171, and 172. These contacts 170, 171, and 172 are arranged in arcuate formation and immediately above them is a graduated scale 173 which is adapted to cooperate with the arm 169.

A terminal block 174 is mounted on the panel 148. A terminal plate 175 is carried by this block and a conductor 176 connects this plate 175 with the contact 170. A cable 177 extends from the plate 175 and is a part of the electrical circuit to be later described. Likewise, another terminal plate 178 is carried by the block 174 and is joined by a conductor 179 with the contact 171. A cable 180 leads off from the terminal plate 178. Still another terminal plate 181 is mounted on the block 174 and is connected by a conductor 182 with the contact 172. A cable 183 leads off from the plate 181. A light 184 is mounted on the block 174 and illuminates the interior of this unit. It will be noted that a cable 185 is connected to the contact arm 169 as indicated at 186. A cable 187 which is broken to include the connections for the light 184 branches off from this cable 185.

While the modus operandi of the control unit C is believed to be self-evident from the foregoing description, it may be noted that as the paper P moves between the caliper rolls 64 and 65 and if the thickness is uniform and of the degree required, the caliper roll 64 will remain immovable with the contact arm 169 engaging the contact 171. This lights up the white light 145 and indicates that the paper being produced is of the proper uniform thickness. Should the paper become too thick the caliper roll 64 will be moved upwardly. This movement will be multiplied by the leverage mechanism so as to move the gear sector 163 in a counter-clockwise direction. This will rotate the pinion 168 and contact arm 169 in a clockwise direction whereby it engages the

contact 172. This will light up the red light shown at 188 in Figure 11 and also bring the motor 100 into operation in a manner to be later described. On the other hand, if the paper should become too thin the caliper roll 64 will lower and cause a movement of the contact arm 169 in a counter-clockwise direction whereby it will engage the contact 170 and light the green light shown at 189 in Figure 11. The motor 100 will also be operated, but in a reverse direction from that described above in connection with lighting the red light.

Manually adjustable cycle control

First referring to Figure 2 it will be noted that the stanchion 146 carries a control unit referred to in its entirety by the reference character X, which is positioned beneath the caliper rolls. This unit may take either the form of the manually adjustable control unit shown in Figure 9, or the automatic control unit illustrated in Figure 10. The manually adjustable unit of Figure 9 will now be described.

A supporting member is shown in the form of a panel 190. Mounted on one face of this panel 190 is an angle bracket 191 providing an outstanding shelf 192. Mounted on the shelf 192 is a motor 193 having a driving shaft 194. Drivably carried by the shaft 194 is a worm 195 which engages a worm gear drivably mounted on a vertical shaft 196. Drivably carried on the upper end of the shaft 196 is a pinion 197 that meshes with a gear 198. The latter is drivably mounted on the upper end of a spline shaft 199 that splinably engages collar 200. The lower end of this collar 200 carries a friction disc 201, the peripheral edge of which is in engagement with the face of a driving disc 202. The latter is drivably mounted on a shaft 203 that is journaled in the panel 190.

It is evident that the speed at which the shaft 203 is driven depends on the radial distance of the disc 201 from the shaft 203. The closer the disc 201 is to the shaft 203 the greater the speed of rotation of the latter, and conversely, the farther the distance of the disc 201 from the shaft 203 the lesser the speed of rotation. To the end of varying the effective distance of the disc 201 from the shaft 203 the collar 200 carries a pin 204 outstanding therefrom. This pin 204 is received in a slot 205 which is of the sinuous formation illustrated for a purpose to be later described. The slot 205 is formed in an arm 206 that is pivotally mounted as indicated at 207 on the panel 190. The free end of the arm 206 takes the form of an arcuate segment 208, the peripheral edge of which is formed with calibrations 209 which cooperate with a pointer 210 that is carried by the panel 190. The segment 208 is formed with an arcuate slot 211. A headed bolt 212 extends through the slot 211 and has its inner end screwed into a block 213 carried by the panel 190. This bolt 212 urges a washer 214 against the segment 208 and serves to hold the latter in an adjusted position.

Drivably mounted on the shaft 203 is a cam 215 having a peak 216. A lever 217 is pivotally mounted as represented at 218 on the panel 190 and is biased by a tension spring 219. The free end of this lever engages the peripheral surface of the cam 215 and is held in such engagement by the spring 219. The opposite end of the lever 218 carries a contact 220. Another lever 221 is pivotally mounted, as represented at 222, on the panel 190. The free end of this lever takes the

form of an arcuate segment 223 formed with an arcuate slot 224 and provided with calibrations 225. The latter cooperate with a pointer 226 carried by a block 227 which is mounted on the panel 190. A headed screw 228 passes through the slot 224 and has its inner end anchored in the block 227. The head of the screw 228 clamps a washer 229 against the arcuate segment 223 to lock the lever 221 in an adjusted position. The lever 221 carries a contact 230 which is connected to a cable 231 by a conductor 232. Likewise, the contact 220 is connected to a cable 233 by a conductor 234.

The control unit X is provided for the purpose of determining the length of a cycle. It is to be remembered that when the gate 12 is to be moved, either with a closing or opening movement, it will move a certain predetermined distance for each cycle. The length of the cycle, in terms of time, should be exactly the time which it takes the stock to travel from the outlet 11 to the caliper rolls 64 and 65. One cycle consists of a complete revolution of the cam 215 or, in other words, a complete revolution of the disc 202. The latter can be driven faster or slower depending on the relative position of the friction disc 201 with respect to the shaft 203. The latter may be adjusted by loosening the bolt 212 and swinging the arm 206.

It will be noted that the calibrations 209 are uniformly spaced apart. With this arrangement it is necessary that the slot 205 be of the sinuous formation illustrated because adjustment of the arm must accommodate the fact that the stock travels from the outlet 11 to the cylinder vats at a constant velocity regardless of the speed at which the machine is operating.

The cables 231 and 233 are included in the circuit of the coils 247 and 250 of switches *a* and *b* which operate the motor 100. The length of time during which the contacts 220 and 230 remain in engagement determines the duration of operation of the motor 100 for each cycle. This time period during which these contacts 220 and 230 will remain in engagement may be adjusted by varying the position of the arm 221. This can be done by loosening the headed screw 228 and then again tightening it after the desired adjustment has been made.

The operation of the unit X may be briefly outlined by noting that the motor 193 drives the soline shaft 199, the latter drives the collar 200 and friction disc 201. The engagement of the peripheral edge of the latter with the disc 202 rotates the disc 202 and the shaft 203. This rotates the cam 215. As the cam 215 is rotated in a clockwise direction the lever 217 is raised and at a predetermined point the contacts 220 and 230 engage and complete the circuit for the motor 100. This engagement is maintained until the end of the lever 217 rides off the peak 216, whereupon the lever drops under the influence of the spring 219 and separates the contacts 220 and 230.

Electrical circuit

Before describing the electrical circuit it will be noted from Figures 2 and 3 that the machine includes a main drive shaft 235, the speed of operation of which determines the speed of operation of the machine.

The tachometers represented at 236 and 237 in Figure 11 are operated by a magneto 238 which is driven by the shaft 235.

A source of three-phase alternating current is

represented at 239 and from this source three power lines 240, 241 and 242 lead into the machine. A pair of reversing switches are represented at *a* and *b* and these switches control the delivery of the current to the motor 100. When the switch *b* is closed the motor 100 is operated in a direction to close the gate 12, whereas, when the switch *a* is closed the motor is operated in a reverse direction to open the gate 12.

Three main switches are represented at *e*, *f* and *g*. The switch *e* controls the circuit to the red light 188 and also the energizing of the motor 100 for operation in one direction as will be later described. Likewise, the switch *f* controls the white light 145 and when this light is illuminated maintains the circuit to the motor 100 open, while the switch *g* controls the circuit to the green light 189 and provides for energizing of the motor 100 in an opposite direction from that caused by the switch *e*.

A relay for the switch *e* is represented at *e'*. A relay for the switch *f* is represented at *f'*; and a relay for the switch *g* is represented at *g'*.

Operation

The operation of the control mechanism provided by this invention will now be described in conjunction with the manually adjustable unit X.

The caliper roll 64 is first adjusted so that it is separated from the roll 65 a distance exactly equal to the thickness of the paper which is to be made. This is accomplished by operating member 6 which, through shaft 7 and block 9, moves the pivot 159. This action moves the lever 158 and thus the U-shaped plate 154-156. As the roller 64 is carried by the arm 154, it is adjusted by this movement. For example, if the paper being made is to be .040 inch in thickness, then the rolls 64 and 65 are set so that they are separated exactly .040 inch. In this position and with paper .040 inch in thickness between the rolls the contact arm 169 is in engagement with the central contact 171 as depicted in Figures 6 and 7.

In this position both the switches *a* and *b* are open and no current is delivered to the motor 100. However, the circuit through the cables 180 and 187 is closed to energize the relay coil 243, thereby closing the relay *f'* and energizing the relay coil 244. This closes the switch *f* and completes the circuit from the power line 241 through switch *f* to the white light 145. This indicates that the machine is operating to produce paper of the required uniform thickness.

While the motor 193 is continuously operating because it is connected across power lines 141 and 242 and the contacts 220 and 230 will come into engagement in each cycle, the motor 100 is not operated, because both of the switches *a* and *b* are open.

If the paper *P* should increase in thickness the lever system and the control unit C will be affected to move the contact 169 in a clockwise direction causing it to be disengaged from the contact 171 and engaged with the contact 172. This breaks the circuit to the white light 145 and at the same time energizes the coil 245 of the relay *e'* to close this relay and energize the coil 246 of the switch *e*. This completes the circuit to the red light 188. At the same time closing of the switch *b* engages contacts in circuit to coil 247 and upon next engagement of the contacts 220 and 230 the circuit through coil 247 is completely closed, switch *b* thereby completing the circuit to the motor 100. This

causes the latter to be driven in proper operation to move the gate 12 in a closing direction. This movement will continue just as long as the contacts 220 and 230 are in engagement. When the end of the lever 217 rides off the peak 218 of the cam, the contacts 220 and 230 separate and operation of the motor is discontinued until these contacts are again closed. Thus the amount of movement on the part of the gate 12 for each cycle depends upon the period of time in which the contacts 220 and 230 are engaged in each cycle. This period may be adjusted by adjusting the arm 221 as above explained.

When the contacts 220 and 230 are disengaged by the arm 217 riding off of the peak 218 of the cam 215, the red light 188 will continue to be illuminated until the decreased amount of stock flowing to the cylinder vats has reached the caliper rolls in the form of reduced thickness of the paper. At this time the caliper roll 64 will lower and if the adjustment were sufficient to correct the condition of increased thickness, the contact 169 will return to engagement with the contact 171, thus extinguishing the red light, lighting the white light, and interrupting the circuit to the motor 100. If this adjustment of the gate 12 was not sufficient to correct the condition, then the contact 169 would move over in closer proximity to the contact 171 but would remain in engagement with the contact 172 until the next time the contacts 220 and 230 were engaged. At this time the gate 12 would be lowered an additional step and this operation would be repeated until the paper was of the thickness for which the caliper rolls 64 and 65 have been set. Under this condition the contact 169 would engage the contact 171 thereby extinguishing the red light and lighting the white light. If the paper were to become thinner than that for which the caliper roll 64 is set, this roll would fall downwardly thereby moving the contact 169 in a counter-clockwise direction.

This contact would leave the contact 171 thereby breaking the circuit to the white light and engage the contact 170 which would complete the circuit to the green light. This is done by energizing the relay coil 248 which would close the relay g'. This would in turn energize the coil 249 of the switch g and thus complete the circuit to the green light 189. At the same time energization of coil 249 engages the contacts in circuit of coil 250 and upon next engagement of the contacts 220 and 230 this circuit would be completed energizing the coil 250 to close the switch g. Thus the circuit to the motor 100 is completed during that time of each cycle in which the contacts 220 and 230 are in engagement. Thus, the gate 12 is moved with an opening movement one step as determined by the time the contacts 220 and 230 are in engagement for each cycle. When the gate 12 has been opened sufficiently far to achieve the desired thickness in the paper the contact 169 disengages the contacts 170 and moves over into engagement with the contact 171 again illuminating the white light.

It is evident that when the form of control unit shown at X and illustrated in Figures 11 and 9 is used, any variation in the cycle must be accomplished manually by loosening the bolt 212 and moving the arm 206. This may be done by the operator who will make such an adjustment to have the cycle conform to the speed at which the machine is running as indicated on the tachometer.

In the above description of the operation of

the control mechanism it has been assumed that one complete cycle exactly corresponds, in theory, to the time it takes the stock to travel from the gate 12 to the caliper rolls 64 and 65. As a practical matter this period is subject to some variation and it is desirable, if not necessary in many instances, to set the cycle for a somewhat longer period than this theoretical interval. Thus, if the actual theoretical time it takes the stock to travel from the gate 12 to the caliper rolls 64 and 65 is one hundred and fifty seconds, the control unit might be set for a cycle of one hundred and sixty seconds.

Automatic variation of cycle

Figure 10 illustrates a modified form of the control unit X which provides for automatically adjusting the cycle to the speed at which the machine is running. The unit for the automatic control is indicated by the reference character Y. It comprises a panel 251 which replaces the panel 190. Outstanding from the face of the panel 251 is a bracket 252 in which is journaled a shaft 253. Drivingly carried at one end of the shaft 253 is a sprocket 254; a chain (not illustrated) passes over this sprocket 254 and also over a sprocket mounted on the main drive shaft 235. Thus, the shaft 253 rotates at a speed that corresponds directly to the speed of the shaft 235 or, in other words, the speed of the machine. Operatively mounted on the shaft 253 is a governor mechanism 255 having a movable collar at 256 which is slidable in the shaft 253 and to which is connected a bracket 257.

The latter is in turn connected to one end of a lever 258 that is pivotally mounted as indicated at 259 on the panel 251. The other end of the lever 258 takes the form of a quadrant 260 that is formed with an arcuate slot 261. A pin 262 that is carried at one end of a lever 263 projects into the slot 261. The lever 263 is pivotally mounted as indicated at 264 on the panel 251 and its opposite end is formed with a sinuous slot corresponding to the sinuous slot 205 on Figure 9.

The remainder of the cycle determining mechanism included in this unit is the same as that described above in connection with Figure 9 and these various parts bear the same reference characters.

It is evident that the speed of rotation of the shaft 253 corresponds to the speed at which the paper making machine is operating. Thus, any variations of speed in the latter will affect the governor 255 to cause rectilinear movement on the part of the movable collar 256. This rocks the lever 258 and thereby moves the pin 262 either upwardly or downwardly depending upon whether the machine has been speeded up or slowed down. This causes a corresponding movement at the opposite end of the lever 263 and thus shifts the disc 201 either closer to the shaft 203 or farther away therefrom to vary the speed of the cycle.

It will be remembered that the basic idea underlying this invention is to have the cycle as determined by the unit Y exactly correspond to the time it takes stock to travel from the outlet of the head box to the calipers 64 and 65. Moreover, the time it takes the stock to travel from the outlet 11 to the cylinder vats is constant. Thus, the arcuate slot 261 is so designed as to cooperate with the sinuous slot 205 and give just the right amount of movement to the collar 200 and disc 201 upon variations in the speed of the machine. The design of these slots 261 and 205

is simply a matter of engineering to provide the design necessary to accomplish this end. The mode of operation of the machine when the automatic unit Y is included therein is substantially the same as that above given.

While preferred specific embodiments of the invention are hereinbefore set forth, it is to be clearly understood that the invention is not to be limited to the exact constructions, mechanisms, and devices illustrated and described because various modifications of these details may be provided in putting the invention into practice within the purview of the appended claims.

We claim:

1. In a cycle control unit for paper making machines; an electric motor, a rotatably mounted cam, driving connections between said motor and said cam, and including means for varying the effective driving ratio, said means comprising a spline shaft, a collar on said shaft, a pivotally mounted lever operatively connected to said collar, means for locking said lever in adjusted position, a friction disc drivingly carried by said collar, a second friction disc engaging the peripheral edge of said first friction disc and drivingly connected to said cam, a second pivotally mounted lever having one end engaging said cam, a movable contact on the other end of said lever, a fixed contact spaced from said movable contact, a pivoted arm supporting said fixed contact, and means for clamping said arm in a plurality of positions to vary the length of time said contacts are closed during one revolution of said cam.

2. In a cycle control unit for paper making machines; an electric motor, a rotatably mounted cam, driving connections between said motor and said cam, and including means for varying the effective driving ratio, said means comprising a spline shaft, a collar slidably and drivingly mounted on said shaft, a pin projecting from said collar, a pivotally mounted lever having a slot receiving said pin, means associated with said lever for locking it in adjusted position, a friction disc, a clutch connecting said collar to said cam, a spring biased pivotally mounted lever having one edge engaging said cam, a movable contact on the other end of said lever, a fixed contact spaced from said movable contact, a pivoted arm supporting said fixed contact, a clamp element for clamping said arm, and indicia on said arm for indicating its clamped position for a determination of the length of time said contacts are closed during one complete revolution of said cam.

3. In a cycle control unit for paper making machines; a pair of normally spaced contacts, one of which is movable, a source of power, operating connections between said source of power and said movable contact for causing said contacts to engage for a predetermined duration at regularly spaced intervals, said connections including a friction disc, a second friction disc having a peripheral edge engaging the face of said first friction disc, a lever operatively connected to said second friction disc, a pin at one end of said lever, a quadrant having an arcuate slot receiving said pin, a pivotal mounting for said quadrant, an arm rigid with said quadrant, and a governor operatively connected to said arm.

4. The combination, in a paper making machine, a head box having an outlet, a gate controlling the effective area of said outlet, a caliper roll located at a point where the paper has

achieved a self-sustaining body, a unit at said head box including a motor for operating said gate, a control unit at said caliper roll and including a movable contact operatively connected to said caliper roll, a cycle control unit included in the electrical circuit of said contact and said motor, said cycle control unit including means for causing said gate moving motor to operate intermittently at regularly spaced intervals when the thickness of said paper at the caliper roll varies from a predetermined thickness, a governor driven by said machine and including a part movable in response to speed variations of said machine, a lever connected to adjust said control unit to vary the duration of said intervals, a pin in said lever, an arm having an arcuate slot receiving said pin, and means connecting said arm to said part for movement therewith.

5. A paper making machine comprising a head box having an outlet, a gate controlling the effective area of said outlet, variable speed conveyor means positioned to receive stock from said box by gravity flow and to convey it while draining and forming, a movable caliper roll located at a point along said conveyor means where the paper has achieved a self-sustaining body and resting on the paper whereby variations in thickness in the paper will cause movement of said roll, mechanism operatively connected to said gate for causing opening and closing movements thereof, the operation of said mechanism being under the control of said caliper roll, and a continuously operating cycle control unit serially connected with said mechanism and including

35 adjustable cycle determining means driven with the conveyor means whereby one cycle of operation of said unit may be adjusted in conformity with the speed of operation of said conveyor

means to substantially conform to the time it

40 takes the stock to travel from said outlet to said caliper roll, and means forming a part of said unit manually presettable for causing operation of said mechanism for a predetermined period of time during each cycle.

45 6. A paper making machine comprising a head

box having an outlet, a gate controlling the effec-

50 tive area of said outlet, variable speed conveyor

means positioned to receive stock from said box

by gravity flow and to convey it by draining and

55 forming into a paper sheet, an electric motor for

moving said gate in opposite directions, a con-

tinuously operating cycle control unit comprising

60 a pair of normally spaced contacts in the circuit

of said motor, means for urging said contacts

65 into engagement for a predetermined duration at

spaced intervals including a rotary cam, a vari-

able speed drive connecting the shaft and cam,

a shaft for driving said cam and means including

70 a movable member for adjusting said variable

speed drive for varying the speed of said cam in

accordance with variations in the speed of oper-

ation of said conveyor means.

7. A paper making machine comprising a head

box having an outlet, a gate controlling the effec-

75 tive area of said outlet, an electric motor for

moving said gate in opposite directions, conveyor

means positioned to receive stock from said outlet

by gravity flow and to convey it while draining

and forming into a paper sheet, a caliper roll

bearing on the paper sheet at a point along said

conveyor means where the paper sheet has a

self-sustaining body, a circuit to said electric

motor under the control of said caliper roll and

including a cycle control unit having an input

shaft, a cam, variable speed driving connections between said shaft and cam, a pivotally mounted lever engaging said cam, a movable contact carried by said lever, a fixed contact adapted for engagement by said movable contact, said contacts being included in the circuit to said motor, and means including a movable arm for adjusting the driving ratio between said shaft and cam in accordance with the speed of operation of said conveyor means.

8. A paper making machine comprising a head box having an outlet, a gate controlling the effective area of said outlet, an electric motor for moving said gate in opposite directions, conveyor means positioned to receive stock from said outlet by gravity flow and to convey it while draining and forming into a paper sheet, a caliper roll bearing on the paper sheet at a point along said conveyor means where the paper sheet has a self-sustaining body, a circuit to said electric motor under the control of said caliper roll and including a cycle control unit having an input shaft, a cam, variable speed driving connections between said shaft and cam, a pivotally mounted lever engaging said cam, a movable contact carried by said lever, a fixed contact adapted for engagement by said movable contact, said contacts being included in the circuit to said motor, and means including a speed governor mechanism for automatically adjusting the speed ratio between said shaft and cam in accordance with the speed of operation of said conveyor means, whereby the time required for one complete revolution of said cam substantially conforms to the length of time for the paper stock to move from said outlet to said caliper roll.

9. A paper making machine comprising a head box having an outlet, a gate movable for varying the effective area of said outlet, variable speed conveyor means positioned to receive stock from said outlet by gravity flow, a caliper roll bearing on the paper sheet on said conveyor where the said sheet has attained a self-sustaining body, a motor for moving said gate and under the influence of said caliper roll, a cycle control unit comprising contacts in the circuit of said motor, means for causing the contacts to be engaged for a predetermined duration at regularly

spaced intervals, speed responsive governor means connected to be driven in unison with said conveyor means and including a movable element, and means responsive to movement of said element for varying the duration of said intervals, said last-named means including a lever and cam mechanism.

10. A paper making machine comprising a head box having an outlet, a gate movable for varying the effective area of said outlet, variable speed conveyor means positioned to receive stock from said outlet by gravity flow, a caliper roll bearing on the paper sheet on said conveyor where the said sheet has attained a self-sustaining body, a motor for moving said gate and under the influence of said caliper roll, a cycle control unit comprising contacts in the circuit of said motor, means for causing the contacts to be engaged for a predetermined duration at regularly spaced intervals, speed responsive governor means connected to be driven in unison with said conveyor means and including a movable element, and means including movement of said element for varying the duration of said intervals, said last mentioned means accomplishing an adjustment of said intervals bearing a non-linear ratio to the speed variations of said conveyor means.
